UNITED STATES PATENT OFFICE.

CONSTANCE M. GAULOCHER AND JAMES N. STACY, OF NEW YORK, N. Y.

PROCESS OF FINISHING WALL-SURFACES.

1,160,708.

Specification of Letters Patent.

Patented Nov. 16, 1915.

No Drawing.

Application filed August 26, 1914. Serial No. 858,666.

To all whom it may concern:

Be it known that we, CONSTANCE M. GAULOCHER and JAMES N. STACY, citizens of the United States, residing at New York, 5 in the county of New York and State of New York, have invented certain new and useful Improvements in Processes of Finishing Wall-Surfaces, of which the following is a specification.

10 This invention aims to disclose a novel method of finishing wall surfaces, and aims further to provide a finish for a wall surface which will take the place of wall paper, calcimining, etc., and which will be inexpensive to use and more attractive in appearance.

Incidentally the invention aims to disclose a process for finishing wall surfaces and a combination of materials to be employed in 20 such process, which will render the wall surface sanitary, capable of being readily washed or otherwise cleaned, and which affords no crevices or hiding places for insects, as is the case in the use of ordinary 25 wall paper.

In carrying out our invention, we first prepare a sufficient quantity of a solution of saltpeter in water, using two pounds of saltpeter to each gallon of water. With this 30 solution, the wall or ceiling to be finished is thoroughly washed. We have found that this solution is highly efficient in clearing the wall surfaces and that it serves also as a germicide. We next prepare a suitable 35 quantity of a solution of alum in water, using two pounds of alum to each gallon of boiling water, and apply this solution to the wall, repeating the application until crystals form. The application of this latter solution to the wall provides against 40 sweating and the consequent discoloring of the wall finish. We next sand paper the wall until a very smooth surface is produced and all crevices and cracks in the wall are 45 filled up. We then prepare a suitable quantity of a sizing consisting of three pounds of linseed oil mixed with each gallon of varnish and apply this sizing with a brush to the wall surface.

50 Prior to applying the sizing, we mix about two pounds of ground asbestos or mineral wool with about one pound of disintegrated silk, wool, wood fiber, cotton, mica, saw-dust, or like substances, either in

their original colors or shades or colored 55 mechanically by the use of any suitable coloring material.

Immediately after the application of the sizing to the wall surface, and while the surface is still damp, the mixture of asbestos 60 or mineral wool, and one or the other, or a combination of the disintegrated materials mentioned above, is blown onto the surface by any suitable machine or instrument until the desired shade and appearance has been 65 obtained. It will, of course, be understood that the mixture of asbestos and disintegrated fibrous material will be caused to adhere to the wall surface by the sizing and that when the sizing has become dry, the 70 particles comprising the mixture will be securely anchored to the surface. It will further be understood that a wall may be finished in the manner above described in a single color or shade, or different mixtures 75 may be employed and applied in any manner to display ornamental figures or designs.

We wish it to be understood that we are not limited in use, in the mixture which is to be blown onto the wall surface, to the 80 particular substances above mentioned, but that various fibrous or scaly substances may be employed, and under some circumstances even finely powdered substances including 85 pulverized mineral wool.

What we claim is:

1. The herein described process of finishing wall surfaces consisting in first washing the surface with a solution of saltpeter and then applying to the surface a solution of alum and allowing the same to dry, and then applying to the surface a sizing, and finally, before the sizing has dried, dusting onto the surface a mass of finely divided particles of a finishing material. 95

2. The herein described process of finishing wall surfaces consisting in first washing the surface with a solution of saltpeter in water, next applying a solution of alum to the surface and allowing the same to dry, 100 then sandpapering the surface to produce a smooth finish, next applying a sizing, and finally, before the sizing has dried, dusting onto the surface or otherwise applying thereto a finely divided mass of a finishing material. 105

3. The herein described process of finishing wall surfaces consisting in first cleaning

the surface, then applying to the surface a solution of alum and allowing the same to dry, then sand-papering the surface to a smooth finish, next applying to the surface 5 a sizing, and finally impinging upon the surface a finishing material before the sizing has dried.

In testimony whereof we affix our signatures in presence of two witnesses.

CONSTANCE M. GAULOCHER. [L. s.]
JAMES N. STACY,

Witnesses:

CHAS. S. GAUBERT,
FRED BURKHARDT.
